GROMMET FOR UMBRELLAS

Joseph Levin, Baltimore, Md., assignor to Umbrella Machinery Corp., New York, N. Y., a corporation of New York

Application April 14, 1949, Serial No. 87,419

1 Claim. (Cl. 24—141)

1

This invention relates to grommets for umbrella covers, and is an improvement over the structure embodied in Patent No. 2,120,959 issued June 14, 1938.

An object of this invention is to provide an improved grommet which can be applied to the cover with existing apparatus and methods, and which in applied position will not present any sharp corner or edges to the fabric which in existing grommets tends to cut the fabric.

In the embodiment of this invention the grommet is formed of a pair of rings which are substantially semi-circular in transverse section so that one ring will seat or nest in the other ring, and the outer ring is provided with prongs which are adapted to be bent over the inner edge of the other or inner ring and then bent upwardly into the concave side of the inner ring. In this manner the inner ring will conceal the prongs so that the prongs cannot catch onto any portion of the fabric.

Further, the outer edge of the rim and the inner edge of the rim between the tongues of one ring and above the edges of the rim of the other ring are of rounded arcuate configuration so as to avoid cutting the fabric.

With the above and other objects in view, my invention consists in the arrangement, combination and details of construction disclosed in the drawings and specification, and then more particularly pointed out in the appended claim.

In the drawing:

Figure 1 is a perspective view looking from the outer side of a grommet constructed according to an embodiment of this invention in applied position of an umbrella cover.

Figure 2 is a fragmentary bottom plan view of the grommet in applied position.

Figure 3 is a fragmentary section taken diametrically through the grommet and a portion of the cover.

Figure 4 is an exploded perspective view of the grommet.

Referring to the drawing, the numeral 10 designates generally an umbrella cover which may be formed of fabric or other flexible material and is formed of a plurality of stitched or otherwise secured together sectors 11. A grommet is secured to the central portion of the cover 10 at a point spaced outwardly from the center thereof as shown in Figures 1 and 2. This grommet comprises an upper or outer ring 12 and a lower or inner ring 14. The upper or outer ring 12 is substantially of semi-circular configuration in transverse section as shown in Figure 3 and the lower ring 14 is also of substantially semi-circular configuration in transverse section, and is adapted to seat or nest into the concave lower side of the outer ring 12. The outer ring 12 has projecting from the inner rim thereof, a plurality of prongs

2

15 which initially project below the inner edge of the outer ring 12 and in the same direction as the curvature of this outer ring.

The prongs 15, as shown in Figure 3, are adapted to be bent outwardly and upwardly into the concave lower side as shown in Figure 3 of the lower or inner ring 14 so that the prongs 15 will be substantially concealed and will be protected by the concave lower side of lower or inner ring 14. By providing the two hollow rings as hereinbefore described, the fabric of the cover 10 will substantially follow the curvature of the two rings forming the grommet so that when the umbrella is in a collapsed position no sharp corners will be presented or come into contact with the cover.

As shown in Figure 3, the edge of the rim 16 of the outer or upper grommet ring 12 may be rounded off so that a smooth arcuate surfaced rim will be provided which will not injure or cut the fabric or the material forming the cover 10. In covers at present in use considerable difficulty is experienced in the use of the flat ring shaped grommets because of the sharp corners of these grommets which tend to injure or cut the cover and thereby shorten the useful life of the umbrella. With the grommet as hereinbefore described, the sharp corners of the grommet have been eliminated and the grommet has been so shaped as to substantially follow the line of the cover, particularly when the cover is in collapsed position. The grommets hereinbefore described can be applied with the apparatus at present in use and in accordance with the present methods of applying the grommet. In practice, the upper ring 12 is magnetically secured to a plunger and the cover 10 is held on a flat surface with the lower ring 14 positioned in axial alignment with the upper ring 12. The upper ring is then pressed downwardly with the prongs 15 piercing the cover 10 and it is understood that there will be provided an anvil or prong bending means beneath the lower ring 14 which will bend the prongs 15 outwardly and then upwardly into the concave lower side of lower ring 14.

I do not mean to confine myself to the exact details of construction herein disclosed but claim all variations falling within the purview of the appended claim.

50 What is claimed is:

55 A grommet for use with a fabric umbrella comprising a pair of separable rings, each having an arcuate cross-sectional configuration, the convex side of one of said rings nesting in the concave side of the other, said rings being so dimensioned that when so seated, their rims are substantially flush, a plurality of equidistantly spaced pointed tongues on the inner edge of the rim of said other ring adapted to be overlapped over the inner edge of the rim of said one ring,

and extend inwardly into the concavity of said one ring, the outer edge of the rim and the inner edge of the rim between the tongues of said other ring and both edges of the rim of said one ring being of rounded arcuate configuration whereby no sharp edges of the rims are exposed to contact with the fabric of said umbrella.
